(57) **CLAIM**

The ornamental design for an automobile body, as shown and described.

DESCRIPTION

FIG. 1 is a front and side perspective view thereof;

FIG. 2 is a rear and side perspective view thereof;

FIG. 3 is a side view thereof;

FIG. 4 is an opposite side view thereof;

FIG. 5 is a rear view thereof;

FIG. 6 is a front view thereof; and,

FIG. 7 is a top plan view thereof.

The broken lines in the drawings illustrate portions of the automobile body that form no part of the claimed design.
